(57) **CLAIM**

The ornamental design for a wireless access point support pole, as shown and described.

DESCRIPTION

FIG. 1 is a front perspective view of the wireless access point support pole showing my/our new design;

FIG. 2 is a back perspective view of the wireless access point support pole;

FIG. 3 is a front elevational view of the wireless access point support pole;

FIG. 4 is a back elevational view of the wireless access point support pole;

FIG. 5 is a right side elevational view of the wireless access point support pole

FIG. 6 is a left side elevational view of the wireless access point support pole; and,

FIG. 7, is a top elevational view of the wireless access point support pole, the bottom elevational view being a mirror image thereof.

The broken lines in the drawings illustrate portions of the wireless access point support pole that form no part of the claimed design. The other broken lines represent environmental subject matter only and form no part of the claimed design.
